US0D1107645S

(12) **United States Design Patent** (10) **Patent No.:** **US D1,107,645 S**
(45) **Date of Patent:** **** Dec. 30, 2025**

(54) **CHARGING BASE**

(71) Applicant: **PAX COMPUTER TECHNOLOGY (SHENZHEN) CO., LTD.**, Shenzhen (CN)

(72) Inventors: **Jingzhou Hu**, Shenzhen (CN); **Shuxian Shi**, Shenzhen (CN); **Yuzhuo Wang**, Shenzhen (CN)

(73) Assignee: **PAX COMPUTER TECHNOLOGY (SHENZHEN) CO., LTD.**, Shenzhen (CN)

(**) Term: **15 Years**

(21) Appl. No.: **29/927,652**

(22) Filed: **Feb. 5, 2024**

(30) **Foreign Application Priority Data**

Aug. 14, 2023 (CN) 202330517359.6

(57) **CLAIM**

The ornamental design for a charging base, as shown and described.

DESCRIPTION

FIG. 1 is a front, right, top perspective view of a charging base showing our design.

FIG. 2 is a rear, left, bottom perspective view thereof.

FIG. 3 is a rear, right, top perspective view thereof.

FIG. 4 is a front, left, top perspective view thereof.

FIG. 5 is a front elevation view thereof.

FIG. 6 is a rear elevation view thereof.

FIG. 7 is a left side elevation view thereof.

FIG. 8 is a right side elevation view thereof.

FIG. 9 is a top plan view thereof; and,

FIG. 10 is a bottom plan view thereof.

The broken lines in the drawings illustrate portions of the charging base that form no part of the claimed design.

1 Claim, 10 Drawing Sheets
